PLUG GAUGES

John S. Bedford, St. Louis, Mo.

Application November 8, 1954, Serial No. 467,484

10 Claims. (Cl. 33—178)

The invention relates to plug gauges, and more particularly to progressive plug gauges of the "go" and "not go" type. The advantages of a progressive gauge over a double-ended gauge are relatively well known. The general disadvantage of conventional progressive plug gauges is that when the "go" member is worn both it and the perfectly good "not go" member must be discarded. My invention provides a progressive plug gauge in which the "go" and "not go" members are entirely separate and can be replaced individually as they wear or become obsolete.

The invention will be more readily understood by reference to the accompanying drawings and the following detailed description in which specific embodiments of the invention are set forth by way of illustration rather than by way of limitation.

In the drawings:

Fig. 1 is a side elevational view of the invention, shown partly in section;

Fig. 2 is a longitudinal sectional view of the handle on an enlarged scale;

Fig. 3 is an end view of the handle;

Fig. 4 is a longitudinal sectional view of one of the gauge members;

Fig. 5 is an end view of the gauge member;

Fig. 6 is a side elevational view of one of the connecting members;

Fig. 7 is an end view of the connecting member;

Fig. 8 is a plan view of the invention embodying a modified form of the handle;

Fig. 9 is a plan view of a key used in the invention;

Fig. 10 is an end view of the key; and

Fig. 11 is a perspective view illustrating the key in use in separating two gauge members from a connector member.

Referring to the drawings, and particularly to the embodiment shown in Figs. 1 to 7, inclusive, the reference letter A denotes a suitable handle which may be formed of metal, wear resistant plastics or the like, and which is provided with tubular end sockets which may be tapered at opposite ends to receive like interchangeable and symmetrical connecting members B, each end of which is adapted to snugly fit the sockets in the handle. As is apparent, one end of any of a series of connector members B may be inserted in an end socket of the handle member A, leaving a projecting end to receive the plug gauge, which is likewise provided with end sockets corresponding to the ends of the connecting members B. As shown, a gauge member C of one outside diameter is fitted to a connector B at one end of the handle A and a gauge member C' of different outside diameter is fitted to the connector at the other end. Each of these gauge members C and C' has a second end socket each adapted to receive a connector member B. The two end connector members B, B are in turn adapted to receive gauge members D and D'. It will be understood that the end gauge members D and D' will be of smaller outside diameter than the corresponding gauge members C and C' con-

2

nected directly to the handle A. Thus, in the general assembly the gauge members C and C' adjacent the handle may be referred to as "not go" members and the relatively smaller members D and D' constitute "go" members.

5 Since the connector members B are identical and interchangeable, and since the end sockets of the handle A and of all the gauge members are alike and adapted to receive either end of any connector member, it will be apparent that the gauges may be reversed so that either end may 10 be used and that any gauge member may be replaced when worn. The taper of the end sockets and of the ends of the connecting members is such as to insure firm adherence between the connector members on the one hand and the gauge members or handle on the other.

In the modified system shown in Fig. 8 a T-shaped handle A' having three legs is substituted for the double-ended handle A of the previously described embodiment, and each of the legs of the handle A' is provided with an end socket adapted to receive a connector member B similar to that employed in the previously described embodiment of the invention wherein a double-ended handle A is employed. Thus, with the T-shaped handle A' (Fig. 8) three "not go" gauge C, C' and C" may be employed and three "go" gauges D, D' and D" may also be employed. A handle with several legs is capable of numerous gauge set-ups, as will be readily apparent.

For the purpose of illustration the various parts of the gauge assembly, namely the handle, connector elements and the gauge elements proper will now be described in further detail but it will be obvious that the invention in its broadest aspects is not limited to such details although the detailed embodiments are preferred.

Referring to the double-ended handle A, this comprises a body member 10 which may be of metal, plastic or the like, and is shown as hexagonal in cross section and provided with like sockets 11 and 12 adapted to receive either end of any one of a plurality of interchangeable connector members B. As shown, the handle A is hollow, the sockets 11 and 12 being connected by a passage 13 to reduce the weight, though it may be solid if desired. The handle A' may be similar to the handle A except that it is T-shaped and is provided with three legs 14, 15 and 16 having end sockets 17, 18 and 19, respectively, similar to the sockets 11 and 12 of the handle A and adapted to receive similar connector members B.

As previously set forth, the connector members B are alike and interchangeable, and accordingly a description of one applies to all. In the form shown in the drawings the connector member comprises a plug 20 which may be of metal, plastic or the like, and may be similarly shaped at its ends 21 and 22, the end portions being adapted to fit sockets in handle A or A', or to fit the sockets of the various "go" and "not go" gauge members C, D, etc. Between the tapered portions 21 and 22 there may be provided a non-tapered portion 23, herein shown as relatively short in comparison to the tapered ends, in which non-tapered portions an aperture 24 may be formed adapted to receive the plug portion of a disconnector key or tool E shown in Figs. 9 to 11 inclusive, to be more fully described hereinafter, but which serves to force the ends of the connector member B from the sockets in which they are housed when it is desired to disassemble the parts of the composite gauge.

The various gauge members C, D etc. are essentially alike except for the outer diameters thereof, and a description of one will accordingly apply to all. As shown in Fig. 4 such gauge member comprises a tubular body 30 of circular cross section, the outside diameter of which in the case of "go" members D, D' and D" is such as to just fit within the opening to be gauged, and in the case of the "not go" members C, C' and C" the diameter is such that it cannot be inserted in the said opening, this

being well known in the art. Each body portion 30 is provided with tapered end socket portions 31, 32 adapted to receive either of the tapered ends 21 or 22 of any one of the interchangeable connector members B.

Since the fit between the tapered ends of the connector members B and the tapered sockets of the handle and gauge members may be tight, a suitable disconnector tool or key E previously referred to may be provided. As shown, the key comprises a handle portion 40 suitable for use as a thumb and forefinger grip, a plug portion 41 rigid with the handle and adapted to be inserted in the aperture 24 of an assembled connector unit B, and an elliptical cam member 42 which is adapted to fit in the space between one end of the gauge handle and the end of the adjacent gauge member or between adjacent gauge members, whereby on turning the finger grip or handle portion 40 of the tool the ends of the connector B may be separated from the sockets in which they have been retained.

The invention has been described in detail for the purpose of illustration but it will be obvious that modifications and variations may be resorted to within the scope of the appended claims without departing from the spirit of the invention.

For example, the particular method herein disclosed of joining the various parts is not essential, nor necessarily the best for all types of application, and other connecting devices could be used, as, for example, a long screw passing through the center of the gauge member or a combination of a screw and a tapered connector or other suitable connecting means, in which case a different form of key would be required, as for example a screw driver.

Among the advantages of the present gauge may be mentioned the following:

1. The gauge may be set up with a progressive gauge at each end, or with the T-handle it can be set up with three gauges, and two dimensions, or three, may be gauged while picking up the part being gauged only once.

2. Elimination of a separate handle for each gauge set-up makes the gauge storage problem simpler and reduces the investment required for the gauge equipment. This, of course, necessitates the marking of each member as is done with gauge blocks.

3. The hollow cylindrical shape will facilitate better heat treatment which will result in a harder surface and longer life for the gauge.

4. The gauge members are reversible. When one end of a gauge member is worn it may be marked and in future set-ups it may be assembled so that the unworn end is used for gauging.

5. The "not go" may get the same amount of wear as the "go" by being used as a "go" member in another set-up, thereby increasing its life many times over what it would be if it were discarded along with the worn "go" member as is done with conventional progressive gauges.

6. The gauge may be set up as a conventional single-ended or double-ended plug gauge for cases in which a progressive gauge cannot be used.

I claim:

1. In a plug gauge, the combination of a handle provided at one end thereof with a tubular socket, a plurality of gauge members each provided with a socket corresponding to the socket in said handle, and a plurality of identical, symmetrical and reversible connector members having end portions receivable snugly and selectively in the sockets of said handle and of said gauge members, whereby the handle and the gauge members may be separably and interchangeably secured together.

2. In a plug gauge, the combination of a handle provided at one end thereof with a longitudinally tapered tubular socket, a plurality of gauge members each provided with a socket corresponding to the socket in said handle, and a plurality of identical, symmetrical and reversible elongated connector members each having tapered end portions receivable selectively in the sockets of said

handle and of said gauge members, whereby the handle and the gauge members may be separably and interchangeably secured together.

3. In a plug gauge, the combination of a handle provided in at least one end thereof with a longitudinally tapered tubular socket, a plurality of elongated gauge members each provided in opposite end portions thereof with sockets corresponding to the socket in said handle, and a plurality of identical and interchangeable elongated connector members each having tapered end portions receivable tightly and selectively in the sockets of said handle and of said gauge members, whereby the handle and the gauge members may be separably and interchangeably secured together.

4. The structure as set forth in claim 1 together with means for forcing said handle and said gauge members apart from said connector member.

5. The structure as set forth in claim 3 together with means for forcing said handle and said gauge members apart from said connector members.

6. In a plug gauge, the combination of a handle provided in at least one end thereof with a longitudinally tapered tubular socket, a plurality of elongated gauge members each provided in opposite end portions thereof with sockets corresponding to the socket in said handle, and a plurality of elongated connector members each comprising a transversely apertured cylindrical intermediate portion and a pair of tapered end portions receivable tightly and selectively in the sockets of said handle and of said gauge members whereby the same may be separably and interchangeably secured together, and means receivable selectively in the apertured intermediate portion of said connector members for forcing the handle and the gauge members apart.

7. The structure as set forth in claim 6, wherein said means comprise a key; a stem provided on said key and rotatably receivable in the apertured portion of said connector members; and a cam provided on said stem and operatively engageable with said handle and said gauge members.

8. A plug gauge comprising in combination, an elongated handle provided in opposite end portions thereof with longitudinally tapered tubular sockets, a pair of elongated gauge members each provided in opposite end portions thereof with sockets corresponding to the sockets in said handle, said gauge members being disposed adjacent the ends of the handle, a second pair of gauge members disposed at the outside of the first mentioned gauge members and provided with sockets corresponding to the sockets in the handle, and a set of identical, symmetrical and interchangeable elongated connector members each having tapered end portions receivable selectively in the sockets of the handle and of the first and second mentioned gauge members, whereby to separably and interchangeably secure the same together.

9. A plug gauge comprising in combination, a substantially T-shaped handle provided in each end portion thereof with a tapered tubular socket, a set of elongated gauge members each provided in opposite end portions thereof with sockets corresponding to the sockets in said handle, said gauge members being disposed adjacent the ends of said handle, a second set of gauge members disposed at the outside of the first mentioned gauge members and provided with sockets corresponding to the sockets in the handle, and a set of elongated identical, symmetrical and interchangeable connector members each having tapered end portions receivable snugly and selectively in the sockets of the handle and of the first and second mentioned sets of gauge members, whereby to separably and interchangeably secure the same together.

10. The structure as set forth in claim 9 together with means for forcing said handle and said gauge members apart from said connector members.
